Primary Examiner — Mitchell Siegel

(74) Attorney, Agent, or Firm — Morris O'Bryant
Compagni Cannon, PLLC(57) **CLAIM**

The ornamental design for the putter, as shown and described.

DESCRIPTION

FIG. 1 is a top front perspective view of a putter of the present invention;
 FIG. 2 is a top view of the putter shown in FIG. 1;
 FIG. 3 is a bottom view of the putter shown in FIG. 1;
 FIG. 4 is a front side view of the putter shown in FIG. 1;
 FIG. 5 is a back side view of the putter shown in FIG. 1;
 FIG. 6 is a right side view of the putter shown in FIG. 1; and,
 FIG. 7 is a left side view of the putter shown in FIG. 1.
 The broken line showing is included for the purpose of illustrating and forms no part of the claimed design.

1 Claim, 6 Drawing Sheets(56)
